UNITED STATES PATENT OFFICE.

FREDERICK LEADBEATER, OF DETROIT, MICHIGAN, ASSIGNOR OF ONE-HALF TO THOMAS C. ROGERS, OF SAME PLACE.

SMOKE-CONSUMER.

SPECIFICATION forming part of Letters Patent No. 388,885, dated September 4, 1888.

Application filed April 5, 1888. Serial No. 269,648. (No model.)

To all whom it may concern:

Be it known that I, FREDERICK LEADBEATER, a citizen of the United States, residing at Detroit, county of Wayne, State of

Michigan, have invented a certain new and useful Improvement in Smoke Consumers; and I declare the following to be a full, clear, and exact description of the invention, such as will enable others skilled in the art to which it applies to make and use the same, reference being had to the accompanying drawings, which form a part of this specification.

My invention relates to certain new and useful improvements in smoke-consuming furnaces; and it consists of the construction of devices and appliances, together with their combinations and arrangements, as more fully hereinafter described, and more particularly pointed out in the claim.

In the drawings illustrating my invention, submitted herewith, Figure 1 is a vertical longitudinal section of a furnace embodying my invention. Fig. 2 is a front elevation of the same. Fig. 3 is a detail view of one of the inlet-flues shown in dotted lines in Fig. 2.

The great points to be secured in a so-called "smoke-consumer," as is well known, is to supply a sufficient quantity of oxygen to the combustion-chamber to render the combustion of the gases perfect, and thereby, in reality, to prevent the formation of smoke, or to render its ignition complete. To accomplish these results in a most efficient and satisfactory manner, and at the same time by an economical device which may readily be applied to any ordinary furnace without injury and without undue waste of time, is the purpose of my invention.

I carry out my invention as follows:

A represents the combustion-chamber of a furnace; B, the grate. C is the front wall of the combustion-chamber; C' C'', the doors thereto. These parts may be of any ordinary construction.

Through the wall of the combustion-chamber, and preferably through the front wall, I introduce one or more flues, D, communicating with the combustion-chamber, and also with an exterior air box or conduit, E, which leads, preferably, to the exterior of the fur-

nace-room—as, for instance, through an adjacent window, F—so as conduct any desired supply of fresh air into the combustion-chamber.

Where a series of flues D are desired to conduct the air from the conduit E into the combustion-chamber, the inner end of the said conduit may be extended across the front of the furnace as a manifold, E', from which the individual flues D lead through the wall of the furnace and open into the combustion-chamber. This arrangement admits the air upon the front of the fuel-bed. I prefer, also, to contract the inner ends of the flues, as shown at d, so as to spread the admitted air in a sheet over the fuel-bed and more uniformly distribute the air thereupon, so as more readily to unite with the products of combustion and facilitate their complete consumption.

It will be convenient, also, to lead the supply-conduit so as to communicate with the flues above the door to the combustion-chamber, and consequently it will be desirable to extend the flues through the wall at an angle downward, so as to discharge the air into proper proximity to the fuel-bed. I prefer, therefore, to construct the flues each with an elbow, as at d', the longer arm of the flue being extended at an obtuse angle to the shorter arm, the latter arm being located, preferably, in a horizontal direction to direct the air substantially straight upon the fuel-bed. The angular direction of the longer arm will carry the flue through the wall in a diagonal direction and will prevent the said flue becoming accidentally detached, as will be readily seen in the accompanying drawings.

I prefer to provide the supply pipe or conduit with any suitable regulating valve or damper, e, whereby the supply of air admitted to the combustion-chamber may be properly controlled.

In some furnaces a single flue D may suffice. In others a series of flues will more evenly and satisfactorily distribute the air in the furnace. By leading the supply-pipe to the exterior the draft will insure an abundant quantity of fresh air, thereby making the combustion perfect and preventing the escape of smoke.

It will be understood that the flues are preferably made in a single piece, the elbow above mentioned being merely an angle in the flue; but I do not limit myself to any particular shape or construction of the flue alone, although it is preferably made angular.

What I claim is—

An air flue constructed with an angle and extending diagonally through the wall of a furnace and communicating with a combustion chamber and an air-supply, the said air-flue having its mouth contracted vertically

and extended horizontally, and having a gradual taper from its mouth outward, whereby the inflowing air is caused to spread over the fire in an even sheet, substantially as set forth.

In testimony whereof I sign this specification in the presence of two witnesses.

FREDERICK LEADBEATER.
